SMOKER'S ACCESSORY

Roland T. Booth, Buffalo, N. Y., assignor to
McDonald Products Corporation, Buffalo, N. Y.

Application February 11, 1937, Serial No. 125,261

11 Claims. (Cl. 131—51)

This invention relates to a smoker's accessory and particularly to improvements in ash receptacles.

The invention provides improvements on the structure of ash receptacles as shown in Parkinson Patent No. 2,004,537, patented June 11, 1935.

The improvements provided by this invention over the above mentioned patent are directed particularly to the new supporting bracket construction and the guide member associated therewith for providing a more efficient support for the closure plates and a suitable guide and guard therefor to prevent users of the accessory from damaging the closure mechanism. This damaging of the closure mechanism may take place in the normal use of the accessory for receiving cigarette stubs and the like, when they are being extinguished and placed in the container, or when the cover is detached from the receptacle at which time it may be handled rather roughly during cleaning. This also subjects the closure mechanism to possible injury and with the present supporting bracket construction and the cooperation of the guide member therewith the damaging of the closure plates or other parts of the closure mechanism is substantially avoided.

In the drawings:

Fig. 1 shows the ash receptacle of the present invention in perspective.

Fig. 2 shows a horizontal cross section taken below the cover and looking upwardly at the bottom of the cover to illustrate the closure mechanism for the discharge opening in bottom plan view in closed position.

Fig. 3 is a vertical cross section taken on line 3—3 of Fig. 2.

Fig. 4 is a side elevation of the cover removed from the receptacle with the closure mechanism, and having parts of the peripheral flange of the cover broken away and shown in section in order to clearly illustrate details of construction.

Fig. 5 is a fragmentary cross section through the upper portion of the receptacle illustrating the structure for detachably mounting the cover on the receptacle.

Fig. 6 is an enlarged detailed cross section taken on line 6—6 of Fig. 4.

Fig. 7 is a disassembled view showing the supporting bracket, the guide member and parts of the operating mechanism with fragments of the closure plates, in perspective.

A receptacle 1 is formed to provide a bottom and upwardly extending cylindrical side structure with an open top. The receptacle may be

of any suitable shape and size to obtain the desired capacity and exterior appearance. Inwardly extending inclined beads 2 terminating in depending bead sections 3 forming stops, are provided at opposite positions on the upper edge of the side wall as clearly illustrated in Fig. 5.

A cover 3 has a normally horizontal peripheral section 4 seated on top of the upper edge of receptacle 1. A peripheral flange 5 is formed at the outer periphery of section 4 and engages over the outer surface of the upper edge of the side wall of the receptacle. A depending cylindrical flange 6 is formed at the inner edge of section 4 extending downwardly into the receptacle and terminating at its lower edge in an inwardly and downwardly tapering section 7. The lower edge of the tapering section 7 terminates in a discharge opening 8 and a flange portion 9 is formed at the inner edge of the tapered section 7 to define the discharge opening and form a seat on which the closure plates 10 may engage and slide.

A pair of bars 11 arranged in adjacent but spaced parallel relation extend diametrically across cover 3 and have their opposite end portions extending through openings in depending cylindrical section 6. One end of each of the bars terminates at the outer face of the flange 6. As shown in Fig. 2 the end of each of the bars 11 terminating with the outer face of flange 6 is arranged so that the corresponding end of one bar is at the diametrically opposite side of the cover from the similar end of the other bar.

The opposite ends of these two bars extend to a point adjacent the inside face of the peripheral flange 5 leaving just sufficient space between the ends of the bars and flange 5 to receive the upper edge of the side walls of receptacle 1. These longer ends of bars 11 are designated 12 and are provided with tapered upper faces 13 as shown in Fig. 3. When the cover is placed on the receptacle as shown in Figs. 2 and 3 with ends 12 out of alignment with inclined beads 2 on the receptacle, the closure may be slidably moved into the position shown in Fig. 3 with section 4 seated on the upper edge of the receptacle.

By turning the cover in a clockwise direction on the receptacle, ends 12 will eventually come in contact with inclined beads 2 on the receptacle so that inclined faces 13 thereof will engage the under edges of beads 2. As this engagement progresses it will be obvious that due to the inclined relation of beads 2, a camming action will take place that will ultimately prevent further rotation of the cover on the recep-

tacle and firmly lock the cover in attached position. In any event the depending bead 3 forming the stop will limit the rotated movement of the cover on the receptacle and thereby insure its being held in locked position.

A supporting bracket 14 is formed of a single piece of sheet metal according to the preferred structure of this invention, as disclosed in the drawings, so as to provide a pair of attaching legs 15, each having a laterally extending securing foot 16 on the free end. Securing feet 16 are provided with openings 17 for receiving rivets 18 extending through openings formed in inclined portion 7 of the cover to secure feet 16 on the underside thereof as clearly shown in Figs. 2 and 4.

Supporting bracket 14 in being formed to provide the spaced legs 15 has the central portion of the piece of material extended laterally to 20 provide a closure supporting projection 19, as clearly shown in Fig. 7, formed with a substantially square opening in the end portion thereof to receive the squared portion of pivot pin 23. Pivot pin 20 is provided with a cylindrical portion 21 that receives the bearing extensions 22 of closure plates 10 for pivotally mounting closure plates 10 in co-planar relation for movement toward and from each other to close and open discharge opening 8 in the cover. In the 30 closed position as shown by the drawings the closure plates are arranged in co-planar relation with their adjacent straight edges in contact. A bearing washer 23 is provided for retaining the closure plates on cylindrical portion 35 21 of pivot pin 20 which has a squared opening to receive the reduced squared extension on the end of the pivot pin. After the bearing washer 23 is applied to the pivot pin the end may be riveted over to permanently retain the 40 parts in assembled relation with the closure plates mounted for free pivotal movement on cylindrical section 21.

Legs 15 depend from the underside of the cover in the manner illustrated in Fig. 4, and are 45 joined in the intermediate portion of the supporting bracket by central section 24. Bearing extension 19 is also joined at one end of central section 24. A pair of side flanges 25 are provided on opposite sides of central section 24 at 50 the end portion opposite to extension 19. These side flanges are provided with openings 26 for receiving pivot pin 27. Rock member 28 is pivotally mounted on supporting bracket 14 by pivot pin 27 extending through openings 26. The 55 closure engaging arms 29 will have the slotted ends thereof embracing projections 30 of closure plates 10 in order that the closure plates may be operated between open and closed position by the rock member when it is moved upon its pivot pin 27 through operation of handle member 31 pivotally connected to rock member 28 by pin 32 at one end and having the opposite end provided with a rectangular head portion 33 slidably mounted in an aperture in flange section 4 60 of the cover. The upper end of head portion 33 projects above flange section 4 as clearly illustrated in Fig. 1 a distance sufficient to provide for manual depression of head portion 33 to secure movement of closure plates 10 to the open 65 position. This rock member 28, handle member 31 and the other features of the movable parts used to actuate closure plates 10 are clearly disclosed and described in the patent mentioned 70 above and further illustration and description

thereof is therefore not essential to a clear understanding of the present invention.

A spring 34 is mounted on pivot pin 32 and arranged so that one end will engage handle member 31 while the opposite end engages pivot pin 27. The tension on this spring is arranged to normally move the parts so that closure plates 10 will be actuated to the closed position and retained in such position by this spring.

The central section 24 of supporting bracket 14 between lateral projection 19 and side flanges 25 is formed with a pair of apertures provided for the attachment of a guide member 35 there-to by having the free ends 36 extending through the apertures in the central section as clearly 15 shown in Fig. 7 and suitably secured to the supporting brackets by soldering or the like. This guide member 35 is illustrated as being formed from a single length of wire arranged so that adjacent to the end sections 36 the wire is formed 20 to provide oppositely extending arcuate sections 37 intermediate the ends of the guide member and at the opposite end of the guide member the central portion of the wire is provided to form a laterally extending small attaching loop 38. 25 At 39 the wire is formed to have the portions at the opposite ends of loop 38 where it is joined to sections 37 in substantial engagement so that loop 38 will be closed. Loop 38 extends at the proper angular relation from sections 37 of the 30 guide member to engage the surface of tapered portion 7 of cover 3 adjacent to flange 9 on the side opposite discharge opening 8 from that at which supporting bracket 14 is located, as clearly illustrated in Fig. 4. Solder or other 35 suitable material is used to rigidly anchor loop 38 to inclined section 7 by placing the solder inside of the loop as indicated at 40 in Fig. 6.

When guide member 35 is secured in this manner at its opposite ends to supporting bracket 14 and inclined portion 7 of cover 3 the oppositely extending arcuate guide portions 37 thereof will be arranged in spaced relation below closure plates 10 as clearly illustrated in Figs. 3 and 4, and substantially parallel to the closure plates 45 and the lower edge of flange 9. Arcuate sections 37 of guide member 35 are of such a size and curvature that they extend around discharge opening 8 below flange 9 in the manner shown in Figs. 2, 3 and 4, in order that passage of waste 50 material from the cover through the discharge opening will not be impeded, while at the same time the guide sections 37 will be present to have the under faces of cover sections 10 ride thereon if a user of the receptacle presses downwardly 55 on the upper faces of the plate in using the device.

Guide or guard member 35 in being arranged as illustrated and described above so as to be secured to the central portion of supporting bracket 14 and to cover 3 at the opposite side of 60 the discharge opening from the supporting bracket, provides a brace member for the supporting bracket so that there are three points of attachment for the supporting bracket to the cover. This provides a very rigid construction that when 65 once assembled holds the supporting bracket rigidly in position with respect to the discharge opening and thereby effectively mount closure plates 10 in such a manner that they are efficiently supported in the proper position for movement between open and closed positions over discharge opening 8 in the cover. If the ash receptacle should fall or be jarred or thrown about during its use as these devices occasionally are, there will be no likelihood of injury to the sup- 70 75

porting structure that would throw the plates out of line and interfere with the operation of the closure mechanism. The supporting bracket 14 has central sections 24 and side flanges 25 thereof extended substantially below rock member 28 as clearly shown in Fig. 4, in order to provide an additional guard for the operating mechanism for the closure plates to prevent injury to the mechanism. It has been found that this extension beyond the lower portions of the rock member or other parts of the operating mechanism will protect the operating mechanism against injury when the cover is separated from the receptacle for cleaning and the like, and is thrown around. This is due to the fact that by reason of the marginal flange 5 on the cover and this projecting guard portion formed by the lower free end of supporting bracket 14 the structure is prevented from being placed in a position with respect to other articles where the other articles would normally come in contact with any part of the operating mechanism. Therefore, through the combined structure of guide member 35 and supporting bracket 14 the closure mechanism is well protected for its normal operation to open and close the discharge opening to allow discharge of ashes and other refuse into the receptacle and to maintain a relationship between the parts that is efficient so as to give the closure mechanism a substantial support and protection for normal operation over a substantial period of time.

The invention claimed is:

1. In a smoker's accessory having a receptacle provided with a cover formed with a discharge opening and a closure for said opening in the form of a plate pivoted for movement to open and close said opening upon the actuation of operating means, the combination of a supporting bracket pivotally mounting said plate, and a guide member for said plate connected to said bracket, said bracket and guide member being connected to said cover at spaced points whereby said guide member cooperates with said bracket to provide a rigid support, guide and guard for said plate.

2. A smoker's accessory comprising a receptacle, a cover for said receptacle having a discharge opening, a supporting bracket mounted on said cover and extending laterally therefrom, a closure plate mounted on said bracket on the under side of said cover for edgewise movement to open and close said discharge opening, operating means for said closure plate, and a guide member underlying said closure plate attached to said bracket and cover at spaced points and cooperating with said bracket to provide a rigid support for said closure plate and for guarding and guiding said plate.

60 3. A smoker's accessory, comprising a receptacle, a cover for said receptacle having a depressed central portion formed with a discharge opening, a supporting bracket mounted on the under side of said cover and depending laterally therefrom, a closure plate pivoted on said bracket for edgewise movement in opening and closing said discharge opening, and a guide member secured at one end to said bracket, having a pair of curved sections following the marginal portions of said discharge opening below said closure plate and having the opposite end attached to said cover at the side of said discharge opening opposite to said bracket, said guide member cooperating with said bracket to provide a rigid support and guide for said closure plate.

4. A smoker's accessory, comprising a receptacle, a cover for said receptacle formed with a discharge opening, a supporting bracket having one end attached to said cover and having the opposite end projecting laterally therefrom, a closure mounting on said bracket spaced from said cover, a closure plate pivoted on said closure mounting for opening and closing said discharge opening, a guide member attached to said bracket and to said cover at the opposite side of said discharge opening from said bracket and cooperating with said bracket for rigidly supporting and guiding said closure plate, and means for actuating said closure plate.

5. A smoker's accessory, comprising a receptacle, a cover for said receptacle having a discharge opening, a closure plate for said discharge opening, a supporting bracket on said cover pivotally mounting said closure plate, a guide member connected to said bracket at one end and to the cover at the opposite end and having a central closure plate guiding section, and means carried by said bracket for actuating the closure plate into open and closed positions.

6. A smoker's accessory, comprising a receptacle, a cover for said receptacle formed with a discharge opening, a supporting bracket mounted on the underside of said cover at one side of said discharge opening, a pair of closure plates pivotally mounted on said supporting bracket for edgewise movement laterally across said discharge opening, a pivoted member on said supporting bracket engaging said plates and operable for moving said plates, a guide member secured at one end to said supporting bracket below said plates, having a guiding section for each plate contiguous to said discharge opening and having the opposite end secured to said cover, and a manually operable member guided in said cover for operating said pivoted member to move said closure plates.

7. A smoker's accessory, comprising a receptacle, a cover for said receptacle formed with a discharge opening, a supporting bracket mounted on and depending from the under side of said cover at one side of said discharge opening, a lateral extension on said bracket, a pair of closure plates pivotally mounted on said lateral extension for edgewise movement laterally across said discharge opening, a pivoted member mounted on said supporting bracket intermediate the ends engaging and operable to move said plates, said supporting bracket having the free end projecting beyond said pivoted member and forming a guard for the parts carried thereby, a guide member having one end attached to an intermediate portion of said supporting bracket below said plates and having guiding sections extending around said discharge opening and the opposite end secured to said cover on the opposite side of said discharge opening from said bracket, and means for operating said pivoted member from the opposite side of said cover.

8. A smoker's accessory, comprising a receptacle, a cover for said receptacle formed with a discharge opening, a supporting bracket secured at one end to said cover at one side of said discharge opening and extending laterally therefrom, a guide member having one end attached to an intermediate portion of said supporting bracket and extending laterally therefrom in spaced parallel relation to said cover, said guide member having an angular extension at the opposite end secured to said cover in spaced relation from said bracket, and a closure mechanism

for said discharge opening mounted on said supporting bracket having movable closure plates between said guide member and cover, and means for moving said plates operable from the opposite side of said cover.

9. A smoker's accessory, comprising a receptacle, a cover for said receptacle formed with a discharge opening, a supporting bracket formed of a piece of sheet metal having a lateral extension at one end secured to said cover, an intermediate lateral extension on said bracket, and side extensions on the free end of said bracket, a guard member secured to an intermediate portion of said bracket at one end, extending in spaced parallel relation to said cover and having the opposite end secured to said cover, and closure mechanism for said discharge opening having closing means movable to close or open said opening mounted on said intermediate lateral extension and projecting between said cover and guard member and actuating means for said closing means mounted on said side extension and operable from the opposite side of said cover.

10. A smoker's accessory, comprising a receptacle, a cover for said receptacle formed with a discharge opening, a supporting bracket depend-

ing from said cover at one side of said discharge opening, a pair of plates pivoted on said supporting bracket for edgewise movement to open and close said discharge opening, means for actuating said plates from the opposite side of said cover, and a guard member secured to an intermediate portion of said supporting bracket having a pair of oppositely curved intermediate sections disposed on the opposite side of said plates from said cover and having a loop formed at the opposite end secured to said cover.

11. A smoker's accessory, comprising a receptacle, a cover for said receptacle formed with a discharge opening, a supporting bracket depending from said cover at one side of said discharge opening, a closure mounted on said bracket movable to open and close said discharge opening, means for actuating said closure operable from the opposite side of said cover, and a guard member formed of a piece of wire having a loop formed in the central portion secured to said cover, a pair of oppositely curved sections extending from said loop for guiding and guarding said closure in operation and the ends of said wire having a connection with said supporting bracket.

ROLAND T. BOOTH.
